UNITED STATES PATENT OFFICE.

ADOLPH E. HERMANN, OF RAVENNA, OHIO.

SPRING-VEHICLE.

SPECIFICATION forming part of Letters Patent No. 277,032, dated May 8, 1883.

Application filed December 1, 1882. (No model.)

To all whom it may concern:

Be it known that I, ADOLPH E. HERMANN, of Ravenna, Portage county, Ohio, have invented a new and useful Improvement in Spring-Vehicles, of which the following is a specification.

My invention relates to spring-vehicles in which the axles are not connected by a reach, the front axle, to which the draft is applied, being connected by means of jointed rods with the vehicle-box.

In the drawing forming a part of this specification, the figure is a side elevation.

The front axle is in section, and only the part of the box with which the axle is connected is shown in the drawing. The front axle, x , and spring w , and block v , and fifth-wheel n are attached together in the usual manner. Fifth-wheel n turns in contact with its counterpart n' , which has one or more arms, m , extending from it and attached to box b , and also has a lug, o , projecting from it, to which rod c is jointed or hinged. Axle x and the lower part of spring w turn in clip e on pin p , which extends through them and clip e . Rod s is jointed or hinged to clip e and the lower ends of rods c and a . The other end of rod a extends back and is hinged to the bottom of the vehicle.

When the springs of the vehicle are compressed, rod s , moved by rods c and a , turns down on its pivot in clip e , carrying the lower or front end of rod a downward and forward,

thereby relieving axle x from the strain which would otherwise necessarily ensue. It is obvious that the same result will follow if the greater weight be at either end of box b . If the greater weight be on the front spring, w , it will force down the rods c and a , and the strain on axle x will be relieved by rod a drawing down or compressing the rear spring. As the lower or forward end of rod a is hinged to rod s below the point where rod s is hinged to clip e , if the greater weight be at the rear end of box b , it will force down rods s and c and compress spring w , and thereby relieve axle x of the strain which would otherwise result. Axle x is relieved from the strain caused by the draft by rod c , which acts as a brace to rods s and a . It is not essential that the upper end of rod c be connected with lug o on the part n' , as it may be directly connected with box b . The location of the fifth-wheel may also be changed by placing it between axle x and spring w . In that case box b may be attached to block v , as the spring w will not turn with axle x when so arranged.

I claim as my invention—

The three hinged or jointed rods a , c , s , in combination with the axle x and box b , substantially as described.

ADOLPH E. HERMANN.
